LELAND INGERSOLL, OF CLEVELAND, OHIO, ASSIGNOR TO THE A. S. GILMAN PRINTING CO., OF CLEVELAND, OHIO, A CORPORATION OF OHIO.

MANIFOLD-FORM SHEET.

1,385,832.

Specification of Letters Patent. Patented July 26, 1921.

Application filed August 13, 1919. Serial No. 317,248.

To all whom it may concern:

Be it known that I, LELAND INGERSOLL, a citizen of the United States, resident of Cleveland, county of Cuyahoga, and State of Ohio, have invented new and useful Improvements in Manifold-Form Sheets, of which the following is a specification, the principle of the invention being herein explained and the best mode in which I have 10 contemplated applying that principle, so as to distinguish it from other inventions.

My invention relates to perforated sheets and particularly to devices of this character assembled in multiple to provide a manifold form. These multiple sheets are assembled together and are thus inserted in a continuous billing machine from which they are removed after the operation therein is completed and then individually inserted as 20 desired in the loose leaf ledger, temporary binder, transfer binder, etc.

The annexed drawing and the following description set forth in detail certain means embodying my invention, the disclosed 25 means, however, constituting but one of the various mechanical forms in which the principle of the invention may be applied.

The figure of the annexed drawing represents a front face view of one of my 30 improved manifold form sheets.

It has been customary heretofore to make up a manifold form of a plurality of sheets; and to insert the same in the printing machine and then, after the desired subject- 35 matter has been printed on the several sheets, remove the form from the printing machine and separate the sheets. One or any number of these individual sheets are provided with suitable filing means such as 40 round holes and with continuous slots connecting an edge of the sheet with said filing holes. These continuous slots which are provided for the purpose of enabling the insertion of the sheet in the binder and the removal therefrom are a source of annoyance 45 and considerable trouble when printing the subject-matter upon the multiple forms.

This trouble is caused by the catching of the loose edges of the slots in the carbon- 50 carrying attachments. To obviate this difficulty and at the same time provide my improved sheet with means whereby the same may be individually inserted in and removed from the binder, I have designed a sheet 55 shown in the accompanying drawing, a description of which, in detail, will now be given.

As shown in the accompanying drawing, an individual sheet is indicated by the ordinary 1 and the same is formed with filing 60 means, such as slots 2. Instead of these slots 2 being connected with an edge 4 of the sheet by means of continuous slots, I connect said edge 4 and said filing slots 2 by a series of perforations 3. These perforations do not 65 cause the trouble heretofore described as attaching to the continuous slots since the edge where the slot is, as well as all the other edges, are whole or continuous so that there is no projecting angle or corner to catch in 70 the carbon sheet and, at the same time, after the multiple form has been printed, and the several sheets separated one from the other, a continuous opening from the edge 4 to the filing slots 2 may be formed in the necessary 75 sheets by simply rupturing the sheets along the perforations 3. It will be seen that I thus have a sheet which is whole or continuous for easy manipulation in a type-writing machine and one which can in an instant be ruptured along the indicated line of rupture, by a simple tearing motion,—for ready insertion wherever wanted, among the papers of a file. The far sides of the holes act as stops for any further thrust. 85

I do not desire to limit myself to the particular form of filing means shown, such as slots 2, nor to the particular form of means shown for connecting an edge of the sheet with said filing means, such as a series of 90 perforations 3, but construe the spirit of my invention to include any combination of means covering filing means and means consisting of a single line of perforations or the like disposed intermediately of the same and 95 an edge of the sheet which may by a single operation be conveniently converted into a suitable continuous opening between the edge of the sheet and the filing means, after the sheet has been printed, and which shall 100 offer no impediment to the satisfactory printing of the form.

What I claim is:

A manifold form sheet provided with a comparatively large circular perforation 105 adapted to receive a filing post and located adjacent to one edge of the sheet, and a single line of perforations extending straight from the nearest edge of said enlarged perforation to the adjacent edge of the sheet. 110

Signed by me this 26th day of July, 1919.

LELAND INGERSOLL.
